UNITED STATES PATENT OFFICE.

KARL KIEFER, OF CINCINNATI, OHIO.

CLOSING MACHINE.

Application filed February 20, 1919. Serial No. 278,286.

To all whom it may concern:

Be it known that I, KARL KIEFER, a citizen of the United States, and a resident of Cincinnati, in the county of Hamilton and 5 State of Ohio, have invented certain new and useful Improvements in Closing Machines, of which the following is a specification.

My invention relates to apparatus for 10 closing containers, and its object is to rapidly and effectively close successive ones of relatively large numbers of containers, and more especially to attain these results with containers in which the closures are forced 15 into the openings in the containers and held therein by friction; the particular example herein being such a machine for applying in this way the closures of what are commonly known as "friction-top" cans.

20 A further object is to permit of ready adjustment of the machine to operate in the manner just stated upon containers of various heights.

25 A further object is to combine with the closing operation a conveying operation whereby the containers may be conveniently received into and delivered from the closing apparatus.

In the drawing:

30 Fig. 1 is a side elevation of a closing machine embodying my invention;

Fig. 2 is a partial vertical cross-section on a plane corresponding to the line 2—2 of Fig. 1, enlarged;

35 Fig. 3 is a partial plan view of the machine; and

Fig. 4 is an inverted plan view of part of the conveyor chain.

As here shown, the conveyor part of the 40 machine comprises the supporting means therefor. This conveying part of the machine is made up of two parallel rails 1 formed of angle-bars with upright elements 2 and oppositely outwardly extending elements 3 at the bottoms of the elements 2. To these bottom elements 3 near opposite ends of the rails are fixed the legs 4 and 5, which suitably support the machine on the floor or ground, and preferably have rollers 45 6 permitting the machine to be moved about readily. In the upper part of the legs 4, a sprocket-wheel 7 is journaled horizontally, and in the upper part of the legs 5 a similar wheel 8 is similarly journaled. 50 Through the medium of suitable reducing mechanism 9, a motor 10 drives the sprocket-

wheel 8; this motor 10 preferably being mounted some distance above the rails 1.

The conveyor chain 11 is made up of a plurality of links 12, each comprising forward separated lugs 13 (Figs. 2 and 4), a backwardly extending knuckle 14, and laterally extending flat webs 15. The lugs 13 and knuckle 14 extend down from the lower surfaces of the webs 15, while the knuckle 14 of the link extends back past the rear edges of the webs 15. This chain is put together by bringing the knuckle 14 of each link between the lugs 13 of the succeeding link and passing a pin 16 through the lugs 13 and knuckle. The parts are so proportioned that when these links are thus assembled, the webs 15 lie very close together with their upper surfaces substantially even. The knuckles 14 are recessed to receive the 75 teeth of the sprocket-wheels 7 and 8, and when the chain 11 is mounted on the sprocket-wheels, as shown in Fig. 1, the adjoining parts of each two adjacent links pass between the teeth of the sprocket-wheels. Such a chain is obtainable on the market; and is shown and specifically described herein because it is very suitable for use in the present invention. It will be understood, however, that chains of other specific constructions may be used.

On the inside of each rail 2 are fastened smaller angle-bars or slide-rails 17 by means of bolts 18; the horizontal elements of these bars 17 projecting inwardly at the respective sides and being spaced down slightly from the upper edges of the rails 2. The links of the chain 11 have the lower surfaces of their webs 15 bearing on these horizontal parts of the slide rails 17 with their laterally outward edges coming close to the rails 2 near the upper edges thereof. Preferably, the upper surfaces of the links of the chain 11 lie slightly below these upper edges of the rails 2; so that these rails 2 act as lateral guides for objects placed on the chain as it travels along between said rails 2. It will be seen that with this arrangement so far as described and the motor 10 or other suitable motive apparatus driving the wheel 8 over toward the adjacent end of the machine, the upper stretch of the chain is drawn constantly toward and down over this wheel 8 and travels to the other wheel 7 in a preferably rather slack lower 105 stretch along under the rails 2, as shown clearly in Fig. 1. By this means, articles

such as the containers A placed on the chain near the wheel 7 will be carried along toward the wheel 8. This part of the machine is therefore in itself a conveyor. It is described in detail on account of the novel combination therewith of the means especially directed to suitably closing the containers A as they are thus carried along by the conveyor.

- 10 This closing means comprises the relatively rather large wheel 18 having a preferably flat rim 19, and having fixed in its hub the spindle 20 (Fig. 2) which projects out at both sides and has ball-bearings 21 in 15 upright bearing bars 22. These parts are so proportioned that these bearing bars 22 may extend up parallel to each other close to the respective outer edges of the horizontal base parts 3 of the rails 2. A base 20 or yoke-piece 23 is bolted to the lower surfaces of the bottoms 3 of the rails 2 and projects out at opposite sides thereof where it has bolted to it the upright guides 24 which have suitable guideways on their inner 25 sides receiving the bearing-bars 22 snugly; these bars 22 being held in the guideways of the guides 24 by cover plates 25 and 26 at the bottoms and tops, respectively, of the guides 24. The base-plate 23 has the recesses 27 in its outer edges through which the bearing bars 22 project below it, where the lower end parts of these bearing bars are bolted to opposite ends of a yoke 28. This yoke 28 has a hub 29 at its middle 30 which is internally threaded, and a screw 30 passes up through the hub 29 and has a reduced neck 31 bearing in a central opening in the base-plate 23; a still further reduced and threaded part of this screw 30 35 projecting up past the top of the base-plate between the rails 2, and having a washer 32 and nuts 33 thereon. Thus, the screw 30 is prevented from moving up and down; and when it is turned by means of the hand-wheel 34 fixed on its lower end part, it moves the yoke 28 up or down, as the case may be, and with this yoke moves the bearing-bars 22 and the wheel 18 up or down relatively to the chain 11. A lock-nut 35 is 40 screwed on the screw 30, preferably below the hub 29 where it is readily accessible; and this nut is screwed up against the hub 29 when the wheel 18 has been adjusted to the desired height. Thus, the entire mechanism is clamped in its adjusted position; and the adjustment being along a line within the lateral limits of the closure and wheel contact, lateral angular displacement of the wheel from the container top is avoided. 45
- 50 The approximate construction of the containers A is shown clearly in the sectional view in Fig. 2; it being sufficient to state that such a container generally has an upper opening with a downwardly turned annular flange inside the container, and an upwardly

cupped lid or cover a is formed to fit very tightly all around in this down-turned flange. However, there is a variety of such containers; and it will be understood that the machine is suitable for closing any of 70 these containers or any other kind of container in which the closure is forced thereinto or thereonto. The chief requisite for a container to be operated upon most advantageously by this machine is that the container should not be much higher than it is wide, so that it is not readily overturned.

75 Thus, it will be understood, from the mode of operation in which the chain 11 carries the containers successively under the 80 wheel 18, these containers previously having had their caps, covers, lids or other closures placed loosely therein or thereon, with the wheel 18 adjusted to the proper height above the chain, this cap, cover, lid or other 85 closure is pressed tightly down; as, for instance, in Fig. 2 where the lid is being pressed down in the can top. It will be seen that as the container approaches vertical coincidence with the wheel center, the 90 tendency is somewhat to tilt the container backwards. Hence the desirability that the container should be of the stable form just mentioned. This proportion of the container, however, is a varying consideration, 95 and the use of the machine is not essentially confined to containers of any certain proportions.

99 The chain of the character described, supported on the slide-rails 17 or equivalent 100 means, affords an especially firm support for the containers while passing through the closing means; and although the closing means is readily adjustable to containers of a wide range of heights, the construction 105 and arrangement of parts is such that the bearings of the wheel 18 are very rigidly supported and the machine is effective for work upon relatively large closures and to place these closures in the containers very 110 tightly. At the same time, the machine is very simple and of relatively light construction so that it is readily moved about and does not require the attention of very skilled operators to adjust it and to place it in 115 working order.

120 While certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

125 1. In a closing machine to force closure into position on containers, in combination with a wheel, and carrying means to carry the containers successively under said wheel 130

for closure thereof, bearing means positively supporting said wheel on a substantially horizontal axis, and a single means for positively adjusting said bearing means and 5 wheel up or down relatively to said means that carries the containers.

2. In a closing machine to force closures into position on containers, in combination with a wheel, and carrying means to carry 10 the containers successively under said wheel for closure thereof, bearing means positively supporting said wheel on a substantially horizontal axis, and a single means below 15 said carrying means for positively adjusting said bearing means and wheel up or down relatively to said means that carries the containers.

3. In a closing machine, in combination with a wheel, and means to carry containers 20 successively under said wheel for closure thereof, rails flanking said means that carries the containers and supporting said means, a base-plate fixed to the bottoms of said rails thereacross and projecting laterally outwardly from the respective rails, upright guides fixed to said base-plate where it projects out past the respective rails, bearing bars slidably mounted upright in said guides, bearings in the upper parts of said 25 bearing bars, said wheel being journaled in said bearings, said bearing bars projecting below said base-plate, a yoke fixed to the lower parts of said bearing bars therebetween and having a middle upright threaded 30 aperture, a screw threaded up through said aperture and journaled in the middle of said base-plate, means preventing up-and-down movement of said screw in said base-plate, and means for turning said screw whereby 35 said wheel is adjusted up or down relatively to said means that carries the containers.

4. In a closing machine to force closures into position on containers, the combination of elongated conveying means conveying 45 continuously in substantially rectilinear direction, and comprising a chain made up of links each having substantially flat wings and downwardly projected means articulating the successive links together, and 50 sprocket-wheels for driving and guiding said chain, substantially rectilinear and parallel guiding and supporting means at respective sides of said chain in its upper stretch between said wheels, said flat wings of said 55 chain resting on said supporting means, with their flat upper surfaces substantially in a single plane to receive and firmly support containers placed thereon at random, and a wheel journaled above said upper 60 stretch of said chain on an axis substantially at right angles to the direction of travel of said chain, and positively held to prevent its movement bodily away from said conveying means, whereby the containers are carried by 65 said conveying means under said wheel for

closure as aforesaid by the positive pressure of said wheel.

5. In a closing machine to force closures into position on containers, the combination of elongated conveying means conveying 70 continuously in substantially rectilinear direction, and comprising a chain made up of links each having substantially flat wings and downwardly projected means articulating the successive links together, and 75 sprocket-wheels for driving and guiding said chain, substantially rectilinear and parallel guiding and supporting means at respective sides of said chain in its upper stretch between said wheels, said flat wings 80 of said chain resting on said supporting means, with their flat upper surfaces substantially in a single plane to receive and firmly support containers placed thereon at random, a wheel above said chain, bearing 85 means for said wheel at opposite sides thereof in which said wheel is journaled on an axis substantially at right angles to the direction of travel of said chain, upright guides in which said bearing means, respectively, are mounted to slide up and down at opposite sides of the supporting and bearing means for the chain, said guides being fixed to said supporting and bearing means, and means for adjusting these bearing means up 90 and down in these guides and positively holding said wheel to prevent its movement bodily away from said conveying means, whereby the containers are carried by said conveying means under said wheel for closure as aforesaid by the positive pressure of 95 said wheel.

6. In a closing machine to force closures into position on containers, the combination of elongated conveying means conveying 105 continuously in substantially rectilinear direction, and comprising a chain made up of links each having substantially flat wings and downwardly projected means articulating the successive links together, and 110 sprocket-wheels for driving and guiding said chain, substantially rectilinear and parallel guiding and supporting means at respective sides of said chain in its upper stretch between said wheels, said flat wings 115 of said chain resting on said supporting means, with their flat upper surfaces substantially in a single plane to receive and firmly support containers placed thereon at random, a wheel above said chain, bearing 120 means for said wheel at opposite sides thereof in which said wheel is journaled on an axis substantially at right angles to the direction of travel of said chain, upright guides in which said bearing means, respectively, are mounted to slide up and down at opposite sides of the supporting and bearing means for the chain, said guides being fixed to said supporting and bearing means, a screw journaled upright in said supporting 125 130

and bearing means below said chain, and means positively connected to said bearings and threaded on said screw, whereby said bearings and said wheel are positively adjusted up and down by turning said screw.

7. In a closing machine, the combination of elongated conveying means conveying continuously in substantially rectilinear direction, and comprising a chain made up of 10 links each having substantially flat wings and downwardly projected means articulating the successive links together, and sprocket-wheels for driving and guiding said chain, substantially rectilinear and parallel guiding and supporting means at respective sides of said chain in its upper stretch between said wheels, said flat wings of said chain resting on said supporting means, and said chain hanging slack in its 20 lower stretch between said sprocket-wheels, a wheel over the upper stretch of said chain, bearing means for said wheel supported for up and down adjustment on the supporting and bearing means of said upper stretch of 25 said chain, and adjusting means for adjusting said bearing means and said wheel up and down relatively to said upper stretch of said chain, said adjusting means being under said upper stretch of said chain and over 30 said slack lower stretch.

8. In a closing machine, the combination of relatively long substantially parallel bars, legs fixed to said bars near opposite ends thereof, a conveyor chain having its upper 35 stretch between said bars and supported and guided thereby, means supported on said legs for supporting and driving said chain, the lower stretch of said chain running slack below said lower stretch and said bars, a wheel above said upper stretch, bearing 40 means for said wheel in which said wheel is supported on an axis substantially at right angles to the longitudinal extent of said chain, means fixed to the under side of said 45 bars and extending up at opposite sides thereof and supporting and guiding said bearing means for up and down adjustment, and means engaging this supporting and guiding means and with said bearing means 50 below said bars and upper stretch of chain

and above said lower stretch of chain for adjusting said bearing means and wheel up and down relatively to said upper stretch of chain, for the purposes set forth.

9. In a closing machine, in combination 55 with a wheel and means to carry containers under said wheel for closure of the containers, bearing means supporting said wheel on a substantially horizontal axis for contact of the wheel periphery with the carried containers, and means having adjusting operative connection with said bearing means substantially within the lateral limits of said contact, to vary the distance between the wheel periphery and the means that carries 60 the containers with a minimum lateral angular displacement of the contacting wheel and container surfaces.

10. In a closing machine, in combination with a wheel and means to carry containers 70 to said wheel for closure of the containers, bearing means positively supporting said wheel on a substantially horizontal axis for contact of the wheel periphery with the carried containers, and means having positively 75 adjusting operative connection with said bearing means substantially within the lateral limits of said contact, to vary the distance between the wheel periphery and the means that carries the containers with minimum 80 lateral angular displacement of the contacting wheel and container surfaces relatively to each other.

11. In a closing machine to force closures into position on containers, in combination 85 with a wheel, and carrying means to carry containers to the wheel periphery for rotation of said wheel with its periphery in closure-forming contact with closures on the containers, a screw with its axis substantially 90 perpendicular to and within the lateral limits of said contact, positively holding said wheel and said carrying means at various distances apart for the rotary contact of said wheel with the closures of containers 95 of various dimensions.
